RIBBON CABINET AND WINDING MACHINE.

1,138,598.

Specification of Letters Patent.

Patented May 4, 1915.

Application filed January 15, 1914. Serial No. 812,239.

To all whom it may concern:

Be it known that we, LOUIS W. WORSHAM and JOSEPH A. HAUTIER, citizens of the United States, residing at Houston, in the county of Harris and State of Texas, have invented certain new and useful Improvements in Ribbon Cabinets and Winding Machines, of which the following is a specification.

10 This invention relates to new and useful improvements in a combination ribbon cabinet and winding machine.

15 The object of the invention is to provide a device of the character described wherein

ribbons, such as are used on typewriters, adding machines, cash registers and like machines may be stored in bulk on large reels and from which said ribbon may be quickly transferred to individual machine spools,

20 when desired. At the present time ribbons of this character are manufactured and wound upon the spools from which they are used, by the manufacturer, and so furnished to the dealer and in order to keep a complete

25 stock the dealer must keep on hand all of the different colored ribbons, and ribbons formed of combination of colors, wound on spools to suit the different kinds of machines on which said ribbons are used. On account

30 of the great variety of colors, combination of colors and qualities and grades of inking of the ribbons and in view of the further fact that each type of machine has its own peculiar type of spool, a complete stock of

35 ribbons would not only be very expensive but also very bulky and cumbersome.

In ordinary use there are purple, black, blue, green and brown record ribbon and the same colors of copy ribbon; also the

40 combinations of purple and red, black and red, blue and red, green and red, and brown and red record and the like combinations of colors of copy ribbon; also black and purple, blue and purple record ribbon and black

45 and purple and blue and purple copy ribbon; also black record and purple copy, black copy and purple record, blue record and purple copy, blue copy and purple record, blue and black record, blue and black

50 copy, blue record and black copy, blue copy and black record and green and black record. Each of those different colored ribbons have different grades of inking, light, medium and heavy and furthermore each

55 color and grade must be wound on spools

such as are used on the different types of machines. From the foregoing it is apparent that in order to keep on hand a complete stock of all the different kinds of ribbon used, wound on spools which can be used on the 60 different styles of machines now in common use, it would require a considerable investment and furthermore would require the keeping of a large supply of stock on hand some of which is infrequently called for by 65 the consumer. It is now the custom to discard the spool when the ribbon of a machine has become worn out and purchase a new one with each new ribbon, although the spool may be fit for re-use.

70 It is the object of this invention to provide a device of the character described wherein the dealer can keep the different kinds of ribbon stored, wound in reels, and whereby the desired kind of ribbon may be 75 wound upon the machine spools as it is used. This is entirely practical inasmuch as nearly all of the typewriter ribbon now used is one-half ($\frac{1}{2}$) inch in width, the only difference in the use of ribbons by different machines 80 consisting in different lengths and different designs of spools used.

85 With the above and other objects in view, the invention has particular relation to certain novel features of construction, operation and arrangement of parts, an example of which is given in this specification and illustrated in the accompanying drawings, wherein—

90 Figure 1 is a side elevation of the complete device. Fig. 2 is a plan view thereof. Fig. 3 is a sectional end view thereof. Fig. 4 is a fragmentary side elevation of the winding device. Fig. 5 is a sectional end view of the drive shaft thereof. Fig. 6 95 shows the spool driving spindle and its operative connections. Fig. 7 shows a ribbon reel mounted in its supporting bearings. Figs. 8 and 9 show plan and elevational views, respectively, of said bearings and 100 Figs. 10 and 11 show plan and edge views, respectively, of the hub of said ribbon reel.

105 Referring now more particularly to the drawings, wherein like numerals of reference designate similar parts in each of the figures, the numeral 1 refers to a box-like casing having the covering 2 hinged thereon by means of the hinges 3, 3. This covering is provided with a latch 4, of any desired construction, by means of which it may be 110

secured in closed position. The casing 1 is provided with a plurality of transverse partitions 5, which extend vertically and are spaced a uniform distance apart. The number of these partitions may be varied in accordance with the amount of stock which it is desired to carry, and the partitions are spaced apart a sufficient distance to permit a ribbon reel, such as 6, to be passed edge-wise between any two partitions. The casing is usually of sufficient width to admit two reels of ribbon in each space, as shown in Fig. 3. Each reel is wound upon a disk like hub 7 having a central orifice 8 and this hub rotates on the short shaft 9. The sides of the partitions 5 have U-shaped bearings 10 secured thereto, the bearings of the facing sides of any two partitions being correspondingly arranged, so as to receive the respective ends of the shaft 9 upon which the corresponding reel rotates. The open end of the bearing 10 is above, so that a reel may be readily removed or lifted out of the casing, the ends of the shaft 9 readily sliding out of the bearing, and it is apparent that a reel may be as readily replaced in the casing and when so replaced the respective ends of the shaft 9 will rest in the lower end of said bearing 10. The particular form of bearing, however as well as the particular means of supporting the same, may be varied, but the partitions 5 are thought to be preferable inasmuch as they will serve to prevent the wobbling of the reels 6 and will cause them to rotate true.

Each side of the covering 2 is provided with a row of slots 11 of sufficient length and width to prevent the free end of the ribbons forming the reels 6 to pass therethrough. A slot is provided for each reel and is in alinement therewith, and if it is so desired a label, indicating the character of ribbon, may be secured on the covering 2 opposite each slot, as indicated in Fig. 2.

Secured to the ends of the casing and standing therefrom are the bars 12, 12 whose upper ends are connected by the rod 13. These bars are provided to support the rotatable drive shaft 14 which has bearing 50 therein. This shaft has a crank 15 fixed to one end thereof for the purpose of driving the same, although it is obvious that it may be motor driven if it is so desired.

Slidably mounted on the shaft 14 is the spur gear wheel 16 having the extended hub 17. The shaft 14 may be polygonal in cross section in which case the opening through the hub 17 will be of a corresponding shape. In case the shaft 14 is circular in cross section the spur gear wheel 16 will be keyed thereto. In all cases said gear wheel is slideable on the shaft but rotates therewith.

A frame 18 is provided having two depending forks 19, 19. The upper end of the frame is slideable on the rod 13 and the lower

ends of the fork 19, 19 have suitable bearings through which the shaft 14 passes. These forks embrace the gear wheel 16, as shown, and between them is mounted the spur gear wheel 20 which meshes with the gear wheel 16. This gear wheel 20 is fixed on an axle 21 which rotates in suitable bearings in the prongs 19, 19 and said axle is extended forming a spindle 22. This spindle is provided to receive the ribbon spool 24, of the typewriter. Said spool has a central opening which receives the spindle 22 and said spindle is tapered or frusto-conical in form so that when the spool is placed thereon it wedges on the spindle and will rotate therewith. The central opening of the different spools vary and in some cases it will be necessary to slip a bushing, such as 25, over the spindle to insure a tight fit of the spool thereon.

Rotation may be imparted to the shaft 14 through the crank 15 as this rotation will be transmitted to the spindle 22, and the spool carried thereby, through the gear wheels 16 and 20. The free ends of the ribbons forming the rolls 6 project through the corresponding slots 11 and when it is desired to wind any particular kind of ribbon on a spool said spool may be placed on the spindle 22 and the winding device then moved along on the rod 13 and shaft 14 until the spool is brought opposite the desired reel. The free end of the ribbon may then be manually started on the spool and the crank 15 then turned until the desired quantity of ribbon is wound on the spool. The winding device may, of course, be geared so that any desired number of turns of the crank 15 will fill the spool. Fixed to the frame 18 are two guides 26, 26 one on each side which are alined with the spool 24 and also with slots 11 on the corresponding side of the covering 2 and these guides form tracks over which the ribbon passes in winding onto the spool from the reel.

In order to lock the winding device against movement relative to the shaft 14 we have provided a latch 27 which is pivoted to the hub 17. One end of this latch has an inwardly extending catch 28 which is adapted to project through a corresponding opening on the hub 17. The other end of the latch is extended and seats on a resilient member 29. Shaft 14 has a plurality of notches 30 spaced apart therealong, said notches corresponding in number and spacing to the slots 11 on either side of the cover 2 and the catch 28 is normally held, by the resilient member 29, in engagement with one of said notches. When it is desired to move the winding device along the shaft 14 the extended end of latch 27 may be depressed and the catch 28 thus withdrawn from its corresponding notch. The device may then be moved to the desired

point and the latch released and the catch 28 will be forced into engagement with the alined notch 30 by the member 29 and the winding device locked against movement 5 relative to the shaft 14.

While we have shown only one form of this device it is apparent that the mechanical structure thereof may be varied without departing from the principle of the invention and we hereby reserve the right to make such modifications in the structure thereof as will not depart from the scope of the appended claims.

What we claim is;

15 1. A device of the character described including a casing, means carried thereby whereon a ribbon reel may be mounted, a winding device carried by the casing, said device embodying a spindle and a means for 20 rotating the same, said spindle being adapted to receive and rotate a spool whereon the ribbon from said reel is wound, said winding device being adjustable relative to the casing so as to be brought into alinement 25 with the said reel.

20 2. A device of the character described including a casing, means in said casing for rotatably mounting a ribbon reel and a winding device in connection with the casing, said device embodying a rotatable spool support and means for rotating said support, said winding device being adjustable relative to the said reel.

35 3. A device of the character described including a casing, means in said casing whereon is mounted a ribbon reel, a winding device adjustable relative to the casing and ribbon reel, said device embodying a rotatable spool support and a means for rotating the same, said support being provided to receive and rotate a spool whereon the ribbon from said reel is wound.

40 4. A device of the character described including a casing; means in said casing whereon a ribbon reel may be mounted; a winding device adjustable relative to the casing, said device embodying a rotatable spindle and means for rotating the same; said spindle being provided to receive and rotate a spool whereon is wound ribbon from said reel and a means for locking the winding device against adjustment relative to the casing.

45 5. A device of the character described including a casing, a winding device in connection therewith, said casing and winding device being adjustable relative to each other, a ribbon reel support in said casing, a rotatable spool support operatively connected with said winding device, said spool support being adapted to receive and rotate a spool whereon is wound ribbon delivered from said reel.

60 6. A device of the character described including a casing, a winding device in connec-

tion therewith, a plurality of transverse reel supports in the casing between which reels of ribbon may be mounted, a rotatable spool support operatively connected with the winding device and provided to receive and rotate a spool whereon may be wound ribbon delivered from said reel, said winding device being adjustable relative to the casing, whereby it may be brought successively into alinement with said ribbon reels. 70 75

7. A device of the character described including a casing, a plurality of reel supports therein between which reels of ribbon may be mounted, a covering for the casing, said covering being provided with slots opposite the reels through which the ribbon may pass from said reels, a winding device mounted on the casings and adjustable back and forth relative thereto whereby it may be brought into alinement with the ribbon reels 80 successively, a rotatable spool support operatively connected with the winding device and adapted to receive and rotate a spool whereby said ribbon is wound on said spool. 85

8. A device of the character described including a casing, a plurality of reel supports therein between which reels of ribbon may be mounted, a covering for the casing, said covering being provided with slots opposite the reels through which the ribbon may pass from said reels, a winding device mounted on the casing and adjustable back and forth relative thereto, a rotatable spool support operatively connected with the winding device and provided to receive and rotate a spool whereby said ribbon is wound on said spool and a guide carried by the winding device and movable therewith over which said ribbon passes from its reel to said spool. 90 95

9. A device of the character described including a casing, a plurality of reel supports therein, ribbon reels mounted in said supports, said reels, when mounted, being in alinement, a winding device mounted on the casing and adjustable back and forth relative thereto so as to be brought successively into alinement with said reels, a rotatable spool support operatively connected with the winding device and provided to receive and rotate a spool, whereby said ribbon is wound on said spool and a guide carried by the winding device and movable therewith, over which said ribbon passes from the reel to said spool. 100 105 110 115

10. A device of the character described including a casing, a plurality of reel supports therein, ribbon reels mounted in said supports, the supports being arranged so as to bring said reels, when mounted, into alinement, a covering for the casing, said covering being provided with slots opposite the ribbon reels, through which the ribbon may pass from said reels, a winding device mounted on the casing and adjustable back 120 125 130

and forth relative thereto so as to be brought successively into alinement with said ribbon reels, a means for locking said winding device in a fixed position relative to the casing, a rotatable spool support operatively connected with the winding device and provided to receive and rotate a spool whereby said ribbon is wound on said spool and a guide carried by the winding device and movable therewith over which said ribbon passes from its reel to said spool.

11. In combination a stock cabinet, reels mounted therein, a supporting bar, and a winding device mounted on said bar and so constructed as to permit said winding device to be brought into alinement with any desired reel in said cabinet.

12. The combination with a ribbon cabinet and reels mounted therewith, of a winding

device mounted on said cabinet in such manner that any of said reels and said winding device may be brought into alinement one with the other.

13. The combination with a ribbon cabinet and reels mounted therein, of a winding device mounted on said cabinet in such manner that said reels and winding device may be brought into alinement one with the other and means for revolving one of said devices relative to the other.

In testimony whereof we have signed our names to this specification in the presence of two subscribing witnesses.
